W. O. POWERS

BENCH VISE

Filed Jan. 2, 1923

Inventor

W. O. Powers

By *Watson E. Coleman*
Attorney

UNITED STATES PATENT OFFICE.

WILLIAM O. POWERS, OF WARNER LAKE, OREGON.

BENCH VISE.

Application filed January 2, 1923. Serial No. 610,329.

To all whom it may concern:

Be it known that I, WILLIAM O. POWERS, a citizen of the United States, residing at Warner Lake, in the county of Lake and State of Oregon, have invented certain new and useful Improvements in Bench Vises, of which the following is a specification, reference being had to the accompanying drawings.

10 This invention relates to certain improvements in bench vises and has relation more particularly to a device of this general character of an open top, and it is an object of the invention to provide novel and 15 improved means whereby one of the jaws of the vise may be moved relative to the second jaw.

The invention consists in the details of construction and in the combination and arrangement of the several parts of my improved bench vise whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view partly in side elevation and partly in section illustrating a device 35 constructed in accordance with an embodiment of my invention and in applied position;

Figure 2 is a view partly in front elevation and partly in section of the device as 40 illustrated in Figure 1; and

Figure 3 is a view in top plan of the device as herein disclosed.

As disclosed in the accompanying drawings 1 denotes an elongated arm provided at 45 one end portion with a jaw 2, the opposite end portion of said arm being reduced, as at 3, to provide means whereby said arm may be effectively maintained in applied position with respect to a bench or other 50 supporting structure. The arm 1 is disposed through an opening 4 in a block 5, said block 5 connecting a plate 6 and a brace frame 7. The plate 6 rests upon the top of the bench or other structure and is adapted 55 to be suitably anchored thereto.

The arm 1 in a face thereof is provided

with a transversely disposed recess or groove 8 adapted to register with an opening 9 disposed through the block 5 and insertible through the opening 9 and the registering 60 groove or recess 8 is a tapered pin 10 whereby the block 5 and the arm 1 are effectively locked in a fixed relative arrangement.

The arm 1 at a suitable distance below the block 5 has secured to opposite faces 65 thereof the outstanding plates 11 between which extends and is pivotally engaged, as at 12 an end portion of the arm 14. The arm 14 is of a length to extend through the frame 7 and the end portion remote from 70 the pivot 12 is provided with a jaw 15 which coacts with the jaw 2 hereinbefore referred to.

Threaded through the frame 7 is an operating shank 16, the inner end portion of 75 which is reduced, as at 17. The reduced portion 17 terminates in a ball 18 seating within a socket 19 provided in the arm 14, said ball 18 being retained in the socket 19 by the holding plate 20. Upon requisite 80 turning movement of the shank 16, the arm 14 will be caused to swing toward or from the arm 1 whereby the jaws 2 and 5 may be caused to have gripping action upon the desired work or released therefrom. The 85 outer end portion of the shank 16 is provided with the operating member 21.

Extending laterally from the arm 14 and in opposite directions are the arms 22 terminating in the cross heads 23 positioned in 90 close proximity to the sides of the frame 7. The arms 22 and the associated heads 23 contact with the frame 7 to brace or reinforce the arm 14 and to assure the jaw 15 having proper coaction with the jaw 2. 95

From the foregoing description it is thought to be obvious that a bench vise constructed in accordance with my invention is particularly well adapted for use by reason of the convenience and facility with 100 which it may be assembled and operated, and it will also be obvious that my invention is susceptible of some change and modification without departing from the principles and spirit thereof, and for this reason I 105 do not wish to be understood as limiting myself to the precise arrangement and formation of the several parts herein shown in carrying out my invention in practice except as hereinafter claimed.

I claim:

1. A vise comprising a bench plate and a

frame carried thereby, an arm disposed through said plate, means for securing said plate and arm together, one end portion of the arm being provided with a jaw, a second 5 arm pivotally engaged with the first named arm and extending through the frame, said second named arm being provided with a jaw for coaction with the jaw of the first named arm, and means carried by the frame 10 and associated with the second named arm for moving said second named arm with respect to the first named arm.

2. A vise comprising a bench plate and a frame carried thereby, an arm disposed 15 through said plate, means for securing said plate and arm together, one end portion of the arm being provided with a jaw, a second arm pivotally engaged with the first named arm and extending through the frame, said 20 second named arm being provided with a jaw for coaction with the jaw of the first

named arm, and means carried by the frame and associated with the second named arm for moving said second named arm with respect to the first named arm, said second 25 named arm being provided with laterally directed arms terminating in cross heads co-acting with the frame.

3. A device comprising a block provided with an opening, an elongated arm disposed 30 through the opening in the block, means for locking the arm to the block, a brace frame extending outwardly from the block, a second arm disposed through the brace frame, means for pivotally engaging the second 35 named arm with the first named arm, similar ends of both of the arms being provided with coacting jaws, and means moving the arms one with respect to the other.

In testimony whereof I hereunto affix my 40 signature.

WILLIAM O. POWERS.
